UNITED STATES PATENT OFFICE.

LOUIS F. WESCHE, OF WEBB, IOWA.

FLAG-HOLDER.

1,251,147.

Specification of Letters Patent. Patented Dec. 25, 1917.

Application filed May 28, 1917. Serial No. 171,522.

To all whom it may concern:

Be it known that I, Louis F. WESCHE, a citizen of the United States, residing at Webb, in the county of Clay and State of Iowa, have invented certain new and useful Improvements in Flag-Holders, of which the following is a specification, reference being had to the accompanying drawings.

This invention relates to devices for holding flags, and particularly to an attachment for holding flags on automobiles, though the invention is not limited to this use.

The general object of the invention is to provide a very simple attachment which may be easily applied to an automobile or like structure and which will support either a single relatively large flag or a plurality of smaller flags.

A further object in this connection is to provide a device of this character in which the angle of the flags or the position of the flags may be adjusted.

Another object is to provide a construction as referred to which, when two flags are used, may be so adjusted that the flags are disposed at different angles with relation to each other.

A further object is to provide a device of this character which is very simple, may be cheaply made, easy to put in place, and easily adjusted.

Other objects will appear in the course of the following description.

My invention is illustrated in the accompanying drawings, wherein:

Figure 1 is a longitudinal sectional view of my improved flag holder, the members 12 and 15 being in elevation and the flag staff in section;

Fig. 2 is a vertical sectional view of the holder;

Fig. 3 is a front elevation of the flag holder with the clamping members disposed to support a single flag staff;

Fig. 4 is a like view to Fig. 3, but showing the clamping members disposed so as to engage divergent flag staffs;

Fig. 5 is a view showing the confronting faces of the clamping members;

Fig. 6 is a fragmentary elevation of a portion of an automobile with my improved flag holder applied thereto.

Referring to these figures, 10 designates a cylindrical shell of metal, or any other suitable material, which is supported from deformation at one end by a transverse bar 11.

On the other end of this shell is disposed a plug or cap 12, which may be of wood, metal or any other suitable material, and which is reduced for a portion of its length 60 as at 13, so as to set within the end of the shell, this cap section 12 being centrally perforated and being formed with one or more diametrically extending grooves 14.

Coacting with the cap section 12 is a second cap section 15, which abuts against the outer face of the cap section 12 and is centrally perforated and is also formed with a diametrically extending channel or groove 14^a. There may be one or more of these 70 grooves. Passing centrally through the cap sections 12 and 15 is a tightening screw 16 having a notched head 17, the shank of the screw being screw-threaded for engagement by a nut 18.

For the purpose of attaching this device to any desired part of the automobile, I provide a strap 19, through the middle of which a screw shank 16 passes, the nut 18 being disposed outward of the strap. The strap 80 is provided with a buckle 20.

The confronting faces of the cap sections 12 and 15 may also be formed with a plurality of radiating teeth 21, as illustrated in Fig. 5, whereby to hold the cap sections in 85 their adjusted positions.

In the practical use of this device, the strap is placed around a tubular standard or other part of an automobile, which is designated A in the drawing and tightened 90 and buckled, so that the body 10 is firmly supported upon the standard and projects out therefrom. If one large flag is desired to be supported by the flag holder, the sections 12 and 15 which constitute clamps are 95 brought to such a position that the recesses 14 and 14^a are coincident and will clamp on each side of the flag staff. If, on the other hand, it is desired to dispose two flags having relatively small staffs upon the holder, then the members 12 and 15 are rotated to 100 such a position that the grooves 14 and 14^a will be disposed in divergent or in angular relation and the relatively small staffs of the flags are disposed in these recesses 14 and 14^a (see Fig. 3). When the flag or 105 flags are properly disposed between the clamping sections 12 and 15, then the screws 16 may be turned with relation to the nut 18 by rotating the screw by means of a screw driver, the nut being held from rotation by the strap 19. It will be further seen that a 110

rotation of the screw 16, not only acts to draw the sections 12 and 15 into clamping engagement with each other and with the flag staffs, but that it also tightens up upon the strap 19 so that a very secure holding action is provided for. It will likewise be observed that both of the clamping members 12 and 15 may be rotated around the axis of the holder so that the flags may be disposed in any desired relation or at any desired angle and that when two flags are used, they may be disposed at any desired angle with relation to each other or to the machine. While I have devised this invention for particular use with automobiles as a means for supporting flags or other decorations thereon, I wish it understood that it might be used in other circumstances for more or less like purposes and that I do not wish to be limited to the details of construction which are illustrated.

Having described my invention, what I claim is:

1. A flag holder comprising a tubular body open at its opposite ends, coacting flag staff clamping members rotatably mounted upon one end of the body, a clamping loop adapted to engage an article and passing into the other end of the body, and means disposed within the tubular body for urging said clamping members toward each other and coincidentally drawing the article clamping loop into the body.
2. A flag holder of the character de-

scribed comprising a hollow cylindrical body, a clamping member closing one end of the body and having rotatable engagement therewith and formed upon its outer face with a transversely extending groove, a second clamping member confronting the first and having a transversely extending groove on its inner face, a bolt having an exterior head passing through said clamping members into the interior of the body, a strap through which said bolt passes and having a buckle, the strap extending out of the hollow body, and a nut on the bolt outward of the strap and with which the strap engages.

3. A flag holder of the character described comprising a hollow cylindrical body, a clamping member closing one end of the body and having rotatable engagement therewith and formed upon its outer face with a transversely extending groove, a second clamping member confronting the first and having a transversely extending groove on its inner face, a bolt having an exterior head passing through said clamping members into the interior of the body, and means for holding the body upon a supporting member.

In testimony whereof I hereunto affix my signature in the presence of two witnesses.

LOUIS F. WESCHE.
